UNITED STATES PATENT OFFICE.

GEORGE NORMAN ALBREE, OF SWAMPSCOTT, MASSACHUSETTS.

FITTING FOR AIRPLANES AND THE LIKE.

1,315,695.

Specification of Letters Patent.

Patented Sept. 9, 1919.

Application filed November 28, 1917. Serial No. 204,466.

To all whom it may concern:

Be it known that I, GEORGE NORMAN ALBREE, citizen of the United States of America, and resident of Swampscott, in the 5 county of Essex and State of Massachusetts, have invented new and useful Improvements in Fittings for Airplanes and the like, of which the following is a specification.

This invention relates to fittings for frame-work and more particularly to fittings for connecting the frame members of airplanes and the like having two or more members meeting at a common point and having wires or other bracing members radiating from 15 the common point.

The principal objects of the invention are to provide fittings which possess both strength and lightness, which are simple to construct and easy to apply, which have 20 means for simply and rigidly locking the parts in position, which have means for pivotally attaching frame members thereto, which are readily adaptable to different positions and conditions of usage, and which 25 possess other novel features of utility which will be apparent from the following description and the accompanying drawings, in which—

Figure 1 is an elevational view of the 30 preferred embodiment of the present invention, my improved fitting being illustrated as applied to the fuselage of an airplane;

Fig. 2 is a side elevation of the fitting, 35 viewed from the right of Fig. 1;

Fig. 3 is a perspective view of the fitting; and

Figs. 4, 5, 6 and 7 are perspective views 40 of the four component parts of the fitting.

The present invention is illustrated in 45 my copending application filed on even date herewith and as in the copending application the fitting is applied to an airplane fuselage. The framework of airplanes usually involves four or more longitudinals connected together by means of struts and guy wires, as illustrated in said copending application, and in the attached drawings I have shown a longitudinal 1, vertical and 50 horizontal struts 2 and 3, and guy wires 4, 4^a, 5 and 6. I have also illustrated a main airplane wing at 7 and a king post at 8, the king post extending upwardly from the longitudinal to meet a similar post extending upwardly 55 from the other side of the fuselage, the two posts being intended to support the main

wings by means of guys or stays (not shown). In the particular structure illustrated the horizontal strut is recessed to receive the longitudinal 1 so that the lower portion of 60 the end of the horizontal strut is disposed between the longitudinal and the vertical strut 2, but it will be understood that the longitudinal may be of the same or greater depth than the horizontal strut. 65

My improved fitting, as adapted to apply to the above described environments, comprises the four parts A, B, C and D, illustrated respectively in Figs. 4, 5, 6 and 7. The part A comprises a strap bent to fit 70 around the longitudinal 1 and having its end 9 bent to extend along the upper side of the horizontal strut 3. In the preferred embodiment of the invention the strap A is so bent that the inner end 10 is overlapped 75 by the side portion 11 of the strap although the overlapping of these portions is not essential to a successful fitting. In order to attach guys or stays to the fitting the strap A is provided with lips 12 and 13 extending 80 obliquely from the sides thereof and these lips as well as certain other lips hereinafter described may if desired be reinforced by plates 14. The lips are provided with openings 15 for the purpose of attaching them 85 to the guys. At the top of the part A are provided lips 32 for attaching the king posts 8 to the fuselage as illustrated in Figs. 1 and 2.

The part B comprises a strap bent over the 90 longitudinal 1 and having ends 16 and 17 extending along the horizontal and vertical struts 2 and 3. When the struts 2 and 3 extend from the longitudinal at an angle of 90° with respect to each other as illustrated, the bend 18 in the part B is a right-angle bend, but in any event the bend is preferably made to conform to the surface outlines of the longitudinal and abutting struts. Lips 19 extend outwardly from the 95 end 17 and lips 20 extend upwardly from the end 16 of the part B for purposes hereinafter referred to.

The part C of the fitting comprises a horizontal portion 21 and a vertical portion 105 22 extending upwardly from its outer edge. Lips 23 are provided on the portion 22 for a purpose to be described. The inner end 24 of the part C is bent downwardly so as to be in alignment with the guys 6 to 110 which it is intended to be connected. The part D is provided with a horizontal por-

tion 25, a vertical portion 26 and an oblique portion 27 for purposes which will be described.

When the four parts of the fitting are assembled they occupy the relative positions illustrated in Figs. 1, 2 and 3 and the parts are preferably secured together by spot welding, as indicated by the crosses in Fig. 2, or other suitable manner. When assembled the end 16 of part B surmounts the end 9 of part A and the lips 32 and 20 on these parts lie in juxtaposition with the openings therein in alinement so that a bolt 28 may be passed through the openings in the lips and through the lower end of the king post 8. In a similar manner the lips 19 and 23 on parts B and C also lie in juxtaposition with their openings in alinement so that they form a rigid support for the main wing 7 or other part which it may be desired to attach to the fitting. The part D fits beneath the part C with the ends 24 and 27 juxtaposed in parallel contact with each other. The lower end 17 of part B extends along the outside of the vertical strut 2 and depending end 26 of part D extends along the inside of the vertical strut 2 so that a bolt 29 may be passed through the openings in the ends 17 and 26 and through the strut 2. The lips 11 and 13 on part A are bent at an oblique angle to the sides of the part A so that they will be disposed in alinement with the guys 4 and 5 connected thereto. As above stated, the parts A, B, C and D are preferably secured together, as by spot welding, so as to afford a unitary device; and it obviously follows that instead of forming the parts separately and attaching them together they may be formed integrally. On the other hand, the parts are so related to each other that they are bound together when secured in position even though they are not welded or otherwise secured together, and I therefore desire to protect my improved fitting when the parts are either attached to or detached from each other.

I claim:

1. A fitting for the frames of airplanes and the like comprising a strap having a portion bent to surround a frame member and to overlap upon itself throughout a portion of its length, the outer end thereof being bent outwardly from said overlapping portion.

2. A fitting for the frames of airplanes and the like comprising a strap having a portion bent to surround a frame member and to overlap upon itself, the outer end thereof being bent outwardly from said portion, and lips projecting from the sides of the strap for connection with other frame members.

3. A fitting for connecting a main mem-

ber with members extending laterally therefrom comprising a strap surrounding the main member and overlapping upon itself between the main member and a lateral member, the outer end of the strap being bent outwardly along the side member, and means for securing said end to said lateral member.

4. A fitting for connecting a main member with a member extending laterally therefrom comprising a strap having a portion bent around the main member and having a portion extending along the lateral member, and a second strap bent over the main member and extending along the lateral member over the first strap.

5. A fitting for connecting a main member with a member extending laterally therefrom comprising a strap surrounding the main member and overlapping upon itself between the main member and the lateral member and having its end bent along the lateral member, and a second strap bent over the main member and extending along the lateral member over the first strap.

6. A fitting for connecting a main member with two members extending laterally therefrom comprising a strap bent around the main member and extending along one of the lateral members, and a second strap bent over the first strap and extending along each of the lateral members.

7. A fitting for connecting a main member with two members extending laterally therefrom comprising a strap having one of its ends disposed between the main member and one of the lateral members and being bent around the main member so as to overlap said one end, the other end of the strap being bent along said one lateral member, and a second strap over said first strap, the second strap being bent over the main member and extending along each of the lateral members.

8. A fitting for connecting a main member with two members extending laterally therefrom comprising a strap surrounding the main member and having a lip extending along one of the lateral members, and a second strap bent over the main member and extending along each of the lateral members.

9. A fitting for connecting a main member with two members extending laterally therefrom at approximately right angles comprising a strap having one end disposed between the main member and one of the lateral members and being bent around the main member to overlap said one end, the other end of the strap being bent along said lateral member, and a second strap bent over the main member and extending along each of the lateral members.

10. A fitting for connecting a main member with two members extending laterally

- therefrom comprising a strap extending transversely along one side of the main member and thence longitudinally along one side of each of the lateral members, 5 and a second strap disposed between the main member and one of the lateral members with one end extending longitudinally along a second side of the other lateral member and the other end connected 10 to said first strap.
11. A fitting for connecting a main member with two members extending laterally therefrom comprising a strap extending transversely along one side of the main 15 member and thence longitudinally along one side of each of the lateral members, and a second strap disposed between the main member and one of the lateral members with one end extending longitudinally along 20 a second side of the other lateral member and the other end bent into parallelism with the first strap, the parallel portions of the two straps having lateral ears adapted to be secured together.
- 25 12. A fitting for connecting a main member with a member extending laterally therefrom comprising a strap surrounding the main member, the strap having an end extending longitudinally along one side of 30 the lateral member, a second strap extending along the opposite side of the lateral member, and means joining the two straps together.
13. A fitting for connecting a main member with two members extending laterally 35 therefrom comprising a strap surrounding the main member, the strap having an end extending along one side of one of the lateral members, a second strap bent over 40 the main member and extending along said side of said lateral member and one side of the other lateral member, and a third strap extending along the other side of said first lateral member.
- 45 14. A fitting for connecting a main member with two members extending laterally therefrom comprising a strap surrounding the main member, the strap having an end extending along one side of one of the 50 lateral members, a second strap bent over the main member and extending along said side of said lateral member and one side of the other lateral member, and a third strap extending along the other side of said 55 first lateral member, the second strap being secured to each of the other straps.
15. A fitting for connecting a main member with two members extending laterally therefrom comprising a strap surrounding the main member, the strap having an end 60 extending along one side of one of the lateral members, a second strap bent over the main member and extending along said side of said lateral member and one side 65 of the other lateral member, a third strap extending along the other side of said first lateral member.
- extending along the other side of said first lateral member, and a fourth strap extending along the other side of said second lateral member.
16. A fitting for connecting a main member with two members extending laterally therefrom comprising a strap surrounding the main member, the strap having an end extending along one side of one of the lateral members, a second strap bent over 70 the main member and extending along said side of said lateral member and one side of the other lateral member, a third strap extending along the other side of said first lateral member, and a fourth strap extending along the other side of said second lateral member, the first and third straps being secured to the second strap and the fourth strap being secured to the third strap.
17. A fitting for connecting a main member with two members extending therefrom in such manner as to form with each other an interior and an exterior angle, the interior angle being less than 180° , a strap 80 surrounding the main member with one end extending along the outside of one of the lateral members, a second strap bent over the main member and extending along the outside of each of the lateral members, and 85 a third strap extending from one of the other straps along the inside of one of the lateral members.
18. A fitting for connecting a main member with two members extending therefrom 90 in such manner as to form with each other an interior and an exterior angle, the interior angle being less than 180° , a strap surrounding the main member with one end extending along the outside of one of the lateral members, a second strap bent over 95 the main member and extending along the outside of each of the lateral members, and a third strap extending from the second strap along the inside of one of the lateral members.
19. A fitting for connecting a main member with two members extending therefrom in such manner as to form with each other an interior and an exterior angle, the interior angle being less than 180° , a strap 100 surrounding the main member with one end extending along the outside of one of the lateral members, a second strap bent over the main member and extending along the outside of each of the lateral members, and 105 a third strap extending from the second strap along the inside of said first lateral member.
20. A fitting for connecting a main member with two members extending therefrom in such manner as to form with each other an interior and an exterior angle, the interior angle being less than 180° , a strap 110 surrounding the main member with one end extending along the outside of one of the lateral members, a second strap bent over the main member and extending along the outside of each of the lateral members, and 115 a third strap extending from the second strap along the inside of said first lateral member, the second strap being secured to each of the other straps.
21. A fitting for connecting a main member with two members extending therefrom in such manner as to form with each other an interior and an exterior angle, the interior angle being less than 180° , a strap 120 surrounding the main member with one end extending along the outside of one of the lateral members, a second strap bent over the main member and extending along the outside of each of the lateral members, and 125 a third strap extending from the second strap along the inside of said first lateral member, the second strap being secured to each of the other straps.
22. A fitting for connecting a main member with two members extending therefrom in such manner as to form with each other an interior and an exterior angle, the interior angle being less than 180° , a strap 130 surrounding the main member with one end extending along the outside of one of the lateral members, a second strap bent over the main member and extending along the outside of each of the lateral members, and a third strap extending from the second strap along the inside of said first lateral member, the second strap being secured to each of the other straps.

surrounding the main member with one end extending along the outside of one of the lateral members, a second strap bent over the main member and extending along the outside of each of the lateral members, and a third strap extending from the second strap along the inside of said first lateral member, and a fourth strap extending along the inside of the other lateral member.

21. A fitting for connecting a main member with two members extending therefrom in such manner as to form with each other an interior and an exterior angle, the interior angle being less than 180° , a strap surrounding the main member with one end extending along the outside of one of the lateral members, a second strap bent over the main member and extending along the outside of each of the lateral members, a third strap extending from the second strap along the inside of said first lateral member, and a fourth strap extending along the inside of the other lateral member, the first and third straps being secured to the second strap and the fourth strap being secured to the third strap.

22. A fitting for connecting a main member with a member extending laterally therefrom comprising a strap having a portion bent around the main member and having a portion extending along the lateral member, and a second strap bent over the main

member and extending along the lateral member in parallel contact with the first strap, the two straps having juxtaposed connecting lips extending therefrom. 35

23. A fitting for connecting a main member with two members extending laterally therefrom comprising a strap bent around the main member and extending along one of the lateral members, and a second strap bent over the first strap in parallel contact therewith and extending along each of the lateral members, the two straps having juxtaposed connecting lips extending therefrom. 45

24. A fitting for connecting a main member with two members extending laterally therefrom comprising a strap surrounding the main member, the strap having an end extending along one side of one of the lateral members, a second strap bent over the main member and extending along said side of said lateral member and one side of the other lateral member, and a third strap extending along the other side of said first lateral member, the first and second straps having attachment lips extending therefrom in juxtaposition and the second and third straps having attachment lips extending therefrom in juxtaposition. 60

Signed by me at Hampton, Virginia, this twenty-second day of November, 1917.

GEO. NORMAN ALBREE.
